UNITED STATES PATENT OFFICE.

MAURITZ C. INDAHL, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

TYPOGRAPHIC KEYBOARD MACHINE.

Application filed August 16, 1922. Serial No. 582,238.

To all whom it may concern:

Be it known that I, MAURITZ C. INDAHL, a citizen of the United States, and a resident of Philadelphia, county of Philadelphia, 5 State of Pennsylvania, have invented certain new and useful Improvements in Typographic Keyboard Machines; and I do hereby declare the following to be a full, clear, and exact description of the same, 10 reference being had to the accompanying drawings, forming part of this specification, and to the characters of reference marked thereon.

This invention relates to keyboard machines in which the depression of a key produces a signal in the form of a perforation or perforations in a continuous strip of paper, such strip being later utilized in connection with a second machine which performs 15 mechanical operations in accordance with the signals presented by the controller strip. It relates particularly to keyboard perforating machines for typographic purposes, more especially the well-known keyboard typographic machine widely known and used as the product of Lanston Monotype Machine Co. A machine of this kind is basically disclosed in U. S. Patent No. 944,405, dated December 28, 1909 and includes 20 keys by the depression of which valves are operated to permit air under pressure to operate motors, each valve having its own motor and each motor being connected by a system of levers with punch bars and punches operating in connection with suitable dies to produce perforations in a strip of paper fed through the machine by a step-by-step motion. Generally speaking the depression of any key operates two 25 valves whereby the two corresponding motors are operated and the two punches connected therewith are also operated. The signal produced may be said to have two components, calling each perforation a component 30 of the signal: one of these components, when the controller paper has been applied to the second machine above mentioned, for example a type casting and composing machine such as that basically disclosed in U. S. Patent No. 625,998, dated May 30, 1899, allows air under pressure in said second or casting machine to traverse a pipe and operate a gage on one side of the machine; the other signal component simi-

larly causes the operation of a gage on the other side of this casting machine, the two gages controlling the positioning in two directions at right angles to each other of the matrix case of said casting machine. The signal may, therefore, be regarded as a direct signal since it controls directly the gages by which the position of the matrix case which the signal calls for is determined. Since in the commercial machine there are two hundred twenty-five matrices in the 55 matrix case comprising fifteen rows and fifteen columns, it follows that for positioning the case the controller strip must be sufficient in width to provide, for any one signal, twenty-eight possible perforation locations, it being understood that the last row and the last column of the case require no perforations because the casting machine is provided with a permanent stop or gage on one side of the machine for the last row of 60 the case and a permanent stop or gage on the other side of the machine for the last column. A single perforation signal will therefore locate the case somewhere in the last row or the last column and a no-perforation signal will locate the case at the intersection of the last row and the last column. 65

A justification space signal is produced in the keyboard machine in the same manner as the matrix location signals above referred to except that there is provided for one component a special punch called the space or S punch and for the other component a punch for positioning the matrix case for the casting of this space. The second component of this signal when it reaches the 70 casting machine controls the matrix case to bring it to the proper row while the S component or perforation operates a special motor and associated mechanism for causing the cast 75 to be made with the aid of the normal wedge of the machine in combination with the justification wedges of which there are two. 80

The justification signal is double in that it requires the depression of two justification keys as indicated by the justification scale or drum. The signal produced by the first justification key is composed of two components, one of which operates mechanism in the casting machine to pick out one of the two 85 justification wedges and the other of which indicates the position to which the matrix case is to be moved, and, since the selected 90

100

105

justification wedge is operated by the matrix case this second component of the first justification signal causes the proper positioning of the selected justification wedge. The 5 second justification signal operates with two components exactly as the first and causes the positioning of the second justification wedge.

It will be seen that all of the signals 10 whether they are for type positioning or justification or space indications are direct in that they produce direct results in the casting machine. Moreover, both components of a type signal and one component 15 of each space signal and of each justification signal, are locational.

While this invention relates particularly to machines of the kind discussed, its particular purpose is, by a minimum amount of 20 change in the construction of such machines to reduce the number of punches and corresponding perforation locations in the controller strip whereby the latter may be made considerably narrower. Its object is furthermore to reduce the paper area by altering 25 only the paper tower of the keyboard machine whereby keyboards already in use may be readily converted into paper-saving keyboards by the exchange of the paper tower or a comparatively simple reconstruction 30 thereof. A further object is to produce such result without affecting other functions and operations of the machine, notably its touch or feel to the operator. A further 35 object of the invention is to convert the direct signals of the usual keyboard into signals of a different kind or nature, namely, combination or additive signals in which each perforation does not represent a definite 40 gage to determine location, but indicates a definite value to which the values of the other perforations in the signal are to be added in order to arrive at the representation of the signal as a whole. The 45 casting machine which receives these signals is provided with mechanism comprising elements each of which responds to a particular perforation and adds its value in mechanical effect to the values of the mechanisms 50 operated by the other perforations of the signal. In this way, a combination signal may be produced by a single perforation so far as matrix case movement in one direction is concerned, or by two, three or 55 more perforations. A further object is to produce a structure in which character designating keys are related to two groups of punches each group comprising four punches capable of recording the designations of 60 fifteen characters, the two groups consisting of eight punches capable of recording the designations of two hundred twenty five characters. One group of punches will thus 65 represent a row location in the matrix case of the casting machine, and the other group

a column location thereof. Further objects will be hereinafter pointed out or will otherwise appear in connection with the following description of the mechanism embodying the invention as shown in the accompanying drawings, in which— 70

Fig. 8 is a cross section on approximately line 8—8 of Fig. 1.

The keyboard machine illustrated corresponds with the modern, commercial machine represented in general by Patent 944, 415 previously referred to. It is not necessary to give herein a detailed description of the construction or operation of this machine; it will be sufficient to refer generally to those parts which are illustrated, particularly those parts which co-operate with, or are more intimately related to the mechanism forming the subject of the present invention; for example, the keys 10, key bars 11, valve bars 12 and valves 13, said valves when operated by key depressions allowing air under pressure to traverse pipes 14 leading to pneumatic motors 15 the latter being coupled with levers 16 to which the paper strip perforating punches are operatively connected. Bars 17 are pivotally connected to the levers 16 and correspond with the normal punch bars of the keyboard machine; through levers 18 connected with certain of the normal punch bars 17, and corresponding stop bars 19 and stops 20, the operation of one of such bars 17 will throw up a definite stop forming a part of the measuring mechanism of the machine; the line rack 21, units wheel 22, units rack 23 and units wheel pawl 24; the justification scale or drum is represented by 25 and its spring-and-weight operating mechanism by the character 26; the bell 27 for signaling the approach toward the end of the line of composition and the counting device 28 for indicating the number of lines of composition are also illustrated, in Fig. 2, as well as the rod 29 for operating the paper feed mechanism 30 and the paper winding mechanism 31. The normal punch bars 17 consist of a series 33 in number, and each bar is opera- 130

- tively connected through a lever 16 to its corresponding motor 15. The normal bars designated 1 to 14 (Fig. 3) indicate row locations for positioning the matrix case.
- 5 The bars designated A to N similarly indicate columns of the matrix case. The end bars 15 and O do not carry punches in the normal machine but are merely used so that their motors 15 will overcome the resistance of restoring motor 33 (Fig. 1) coupled with universal bar 32, the latter having a portion engaged by each bar 17 to turn the universal bar against the resistance of its motor 33. This motor 33 is of the same dimension as the motors 15, but with each key struck, two motors 15 are operated and two bars 17 are driven upwardly to turn the universal bar 32. There is also a bar 17 designated .0005 (Fig. 3) and another designated .0075; these 10 bars indicating justification, and a third designated S indicating a justified space. The bars 1 to 15 inclusive, and the bar S are coupled by levers 18, previously referred to, to the appropriate stops 20 of the measuring mechanism. The designations given the normal bars 17 correspond to the designations given the said bars in the known standard machine, but in the adaptation of this invention they do not, with the exception of the .0005 bar, carry punches, but do serve as the means whereby the operation of punches may be controlled or effected in certain groups or permutations hereinafter pointed out.
- 35 According to the present invention the paper tower within which the bars 17 are housed and which supports the paper feed and associated mechanism, is provided with upright plates 34 in which are pivoted converting levers consisting of a vertical series of long, rear levers 35 and a vertical series of short, front levers 36. The rear levers are pivoted in the outside plates 34 and the front levers in the right-hand plate 34 (Fig. 40 2) and the intermediate plate 34. These levers are each in the form of pivoted shafts having radially extending arms 35' connected by a lug engaging rod 36', the arms of the front series extending rearwardly and the arms of the rear series extending forwardly so that the lug engaging rods 36' are located close to and along side of the vertically extending series of motor driven bars 17. These bars 17 are, in accordance 45 with this invention, selectively provided with laterally extending lugs 37; the numbered bars 1 to 14 having these lugs extending forwardly to engage with the under surfaces of the rods 36' of the front converting levers 36 and the lettered bars A to N having these lugs 37 extending rearwardly to engage with the rods 36' of the rear converting levers 35. The bar designated 15 as well as the bar designated O are not provided with lugs. The bar designated .0005 is also without
- 50 lugs, but is provided with a punch so that this bar operates directly to punch the paper. The bar .0075 is provided with a forward lug 37 to engage with the lug engaging rod 36' of the lowermost front converting lever 36. The rod designated S is provided with a rearward lug 37 to engage with the lowermost rear converting lever 35.
- Extending vertically between the rods and shafts of the converting levers are a front series of punch bars 38 and a rear series 39. These punch bars are each provided with a single lug 40 for engaging with the upper surface of one of the rods 36' of the converting levers 35 and 36, whereby each bar is operated from its corresponding converting lever. The punch bars have approaching offsets at the top so that their upper ends 41 extend upwardly directly above the bars 17, the ends 41 of the two series 38 and 39 alternating and all the punch bar ends being provided with punches 42 co-operating with corresponding dies 43 to punch the paper controlled by the feeding mechanism 30 in the usual manner. The converting members or levers, it will be seen, are intermediate the bars 17 and the punches 42.
- 55 From an inspection particularly of Fig. 3 it will be seen that when a normal punch bar 17 is moved upwardly by its motor 15 the lug or lugs 37 on the bar will engage with a rod or rods 36' of the converting levers so as to tilt these levers on their shafts. The upward tilt of a lever will cause the upper surface of the bar 36' thereof to engage with a lug 40 on a punch bar and will cause the corresponding punch 42 to move upwardly and co-operating with its die 43 punch a perforation in the paper which, it will be assumed, is associated in the usual manner with the paper feeding mechanism 30. It is not necessary to describe the operation of all of the bars and levers because such operation is clearly indicated in Fig. 60 3. A few examples will be given, however, to illustrate the converting function of the new construction. If it be assumed that a key is depressed which will cause two bars 37, for example, the bar K and the bar 13 to be driven upwardly it will be seen that instead of causing directly two perforations from these bars the bar K through its three lugs 37 will operate the three rear converting levers, the values of which are indicated 65 as 8, 2 and 1, and these levers through the lugs 40 on the punch bars 39 will operate punches 42 which are indicated as having the values 8, 2 and 1; similarly the bar 13 with its three lugs 37 will operate the three front converting levers 36, the values of which are indicated as 8, 4 and 1, these levers operating, through lugs 40 on the punch bars 38, the punches 42, the values of which are indicated as 8, 4 and 1. The result of this 70 particular key depression is the perforating
- 75 75

- 125 125
- 130 130

of six holes, three holes belonging to the punch bar series 39 and their value being 8 plus 2 plus 1 or 11, and three being of the punch bar series 38, and their value being 8 plus 4 plus 1 or 13. These perforation groups indicate that the matrix case is to be located in the eleventh column and thirteenth row, the signals being indirect and converted from the direct signal to the additive or combination signal. Other examples may be taken to show that in some cases a single punch in each group is operated or two punches or three punches. Since the punches have values 1, 2, 4 and 8 in each group it will be seen that by taking any one of these values singly or adding one, two or three of these values together selectively, any row or any column can be obtained from 1 to 14 the lugs 37 on the bars 17 being selectively disposed to produce these additive combinations. If a justification key is operated so as to elevate the normal punch bar 17 which is designated .0005 as well as a locational normal punch bar, the .0005 bar will perforate directly as usual and the locational punch bar will operate through converting levers to produce a combination signal for locating the matrix case. If the justification bar designated .0075 is elevated it will, as shown in Fig. 3, tilt the converting bar designated .0075 and through it will operate the punch designated .0075. If a space bar or key is depressed the normal bar 17 which is designated S, together with a locational bar 17 will be elevated, the former through its lug 37 operating the converting lever designated S and through it the punch designated S; while the locational bar will operate through converting levers to produce a combination signal for location. The various signals whether for justification or space or character, it will be noted, are combination signals since each key depressed produces a signal for the location of the matrix case, and this signal in each case is a combination signal in contradistinction to the direct signal ordinarily produced. Inasmuch as combination signals are availed of the number of punches is reduced from 31 to 11, and since these punches are grouped at the normal distance apart the width of paper is correspondingly reduced as is particularly shown in Fig. 2; this results in considerable reduction of paper cost. The operating of the keyboard is exactly the same up to the normal punch bars 17, and therefore, the touch or feel of the machine is not affected even though in some cases a single perforation is made, and in other cases a triple perforation is made. Since the alteration to the keyboard is in the paper tower thereof it will be seen that keyboards already in use may be converted into paper saving keyboards by the exchange of the paper tower or a comparatively simple reconstruc-

tion thereof. It will also be observed that the character designating keys are so related to the punches that four punches are capable of recording the designation of fifteen characters, it being also noted that when there is no perforation in the paper a sixteenth character may be provided for because of the provision in the casting machine of a permanent gage in accordance with which the matrix case is positioned when a portion of the controller strip is presented in which there is no perforation. The lack of a perforation is in effect a signal, and the four punches are thus capable of indicating sixteen characters. The four punches produce a component of the signal and the remaining four punches constitute a second component so that eight punches are capable of recording the designations of two hundred twenty five characters, or actually two hundred fifty six characters when the blank signal of the paper is taken into account. Each component of the signal, or each group of punches represents, by combination signals, or single punch signals, or blank signals in each group, a matrix case row or column location, one group representing row locations and the other group representing column locations.

I claim:

1. A keyboard perforating machine comprising a series of bars operated by the depression of keys, said bars being provided selectively with laterally extending lugs, a series of punch bars each provided with a laterally extending lug, punches secured to said punch bars, and converting levers provided with rods positioned to be selectively tilted by the lugs of the first mentioned bars to thereby operate the punch bars and punches by engagement with the lugs of the punch bars.

2. In a keyboard composing machine provided with normal punch bars pneumatically operated directly from the depression of keys and in combination therewith punch bars and punches secured thereto, a converting lever for each punch bar for operating the same, and selectively positioned lugs on the normal punch bars for operating converting levers to actuate a combination of punches from each operated normal punch bar.

3. A typographic keyboard perforating machine comprising key-controlled reciprocating bars provided with selective lugs, converting levers comprising rods with which said lugs engage to operate the levers, punch bars, each provided with a lug for engagement with a rod of one of said levers, whereby the operation of a lever causes the operation of its corresponding punch bar, punches secured to said punch bar and dies for cooperation with said punches to perforate a controller strip.

4. A keyboard composing machine having character designating keys and punches for recording the characters designated, characterized by the provision of four punches capable of recording the designations of fifteen characters, and means whereby the keys will effect the operation of the punches singly or in combination with one or more of the others to produce the desired individual record of each character. 5 55
5. A keyboard composing machine having character designating keys and punches for recording the characters designated, characterized by the provision of eight punches capable of recording the designations of two hundred and twenty five characters, and means whereby the keys will effect the operation of the punches selectively singly or in combination with one or more of the others to produce the desired individual record of each character. 15 60
6. A keyboard composing machine having character designating keys and punches for recording the characters designated, characterized by the provision of two groups of four punches capable of recording the designations of two hundred and twenty five characters, and means whereby the keys will effect the operation of the punches of each group singly or in combination with one or more of the punches of both groups to produce the desired individual record of each character. 25 65
7. A keyboard composing machine comprising character designating keys, two groups of punches for recording the characters designated, one of said groups representing matrix case row location and the other matrix case column location of characters, and means connecting the keys and punches to operate selectively the punches of each group in combination to produce, when a key is struck, a combination signal for the column location of the character designated by the key. 30 70
8. A typographic composing machine comprising keys and punches for recording the designations of said keys characterized by the provision of four punches capable of recording fifteen designations, and means whereby the keys will effect the operation of the punches selectively singly or in combination to produce the desired designations. 35 75
9. A typographic composing machine comprising keys and punches for recording the designations of said keys characterized by the provision of eight punches capable of recording two hundred and twenty five designations, and means whereby the keys will effect the operation of the punches selectively singly or in combination to produce the desired designations. 40 80
10. A keyboard composing machine having character designating keys and punches for recording the characters designated, characterized by the provision of four punches capable of recording the designations of fifteen characters, and means comprising keyboard actuated bars provided selectively with laterally extending lugs, a series of punch bars to which the punches are secured, each punch bar being provided with a laterally extending lug, and converting levers provided with rods positioned to be selectively tilted by the lugs of the first mentioned bars to thereby operate the punch bars and punches by engagement with the lugs of the punch bars, said means effecting the operation of the punches from the keys, singly or in combination with one or more of the others to produce the desired individual record of each character. 45 85
11. A keyboard composing machine having character designating keys and punches for recording the characters designated, characterized by the provision of eight punches capable of recording the designations of two hundred and twenty five characters, and means comprising keyboard actuated bars provided selectively with laterally extending lugs, a series of punch bars to which the punches are secured, each punch bar being provided with a laterally extending lug, and converting levers provided with rods positioned to be selectively tilted by the lugs of the first mentioned bars to thereby operate the punch bars and punches by engagement with the lugs of the punch bars, said means effecting the operation of the punches from the keys, singly or in combination with one or more of the others to produce the desired individual record of each character. 50 90
